UNITED STATES PATENT OFFICE.

ELIJAH MCCOY, OF DETROIT, MICHIGAN.

LUBRICATOR.

SPECIFICATION forming part of Letters Patent No. 357,491, dated February 8, 1887.

Application filed September 8, 1886. Serial No. 213,036. (No model.)

To all whom it may concern:

Be it known that I, ELIJAH MCCOY, of Detroit, in the county of Wayne and State of Michigan, have invented certain new and useful Improvements in Lubricators; and I do hereby declare that the following is a full, clear, and exact description thereof, reference being had to the accompanying drawings, and to the letters of reference marked thereon, which form part of this specification, in which—

Figure 1 is a side view of the invention, partly in section, and showing the steam-dome of the engine and steam-pipe of the condenser. Fig. 2 is a side view of the invention, partly in section, standing at right angles to Fig. 1. Fig. 3 is a detail sectional view. Fig. 4 is a detail sectional view showing the manner of securing the covering to the cylinder. Fig. 5 is a vertical longitudinal section of the reservoir and condenser. Fig. 6 is a cross-section of the same, on line $\alpha\alpha$, Fig. 5, reduced.

This invention relates to improvements in lubricators of the class in which steam is used to aid in feeding the oil to the cylinders and other parts of the steam-engine, being especially adapted for use on locomotives; and it consists in the construction and novel arrangement of parts hereinafter described, illustrated in the drawings, and pointed out in the claims hereto appended.

Referring to the accompanying drawings, A designates the oil-reservoir, and B the condenser, of the construction shown in the drawings.

a is a valve controlling the flow of condensed steam through the tube d , which descends from the condenser into the reservoir.

C is a pipe from the steam-dome c of the boiler of the engine, and c' is a valve controlling the steam in said pipe. The pipe C bends upward and connects with the tube c^2 , rising from the top of the condenser at a point considerably higher than its exit from the dome.

D D are visible feed-tubes rising from the bottom of the reservoir and controlled by the valves d at their tops, and E E are horizontal tubes extending from them below the said valves to the globular casing of the check-valve F, the seat of which is made in the said casing-partition, its stem f rising in a guide-recess in the screw-plug f' of the casing. The

partition e bends downward at the outer side of the valve, and joins the lower side of the tube E, forming with the inner portion of the valve-easing the partial partition of dam G, at the outer end of said tube, a water-reservoir, g , the level of the water in which is above the check-valve, as the dam G is higher than the latter.

H H are oil-feed pipes rising within the cylinder, and having at their lower ends the discharge-nozzles h , which stand upward in the lower ends of the visible feed-tubes, as shown.

H' designates a pipe provided with a suitable valve opening into the lower end of reservoir A, and by which said reservoir can be cleared or emptied of its contents.

The outer end of each tube E enters the side of a steam and oil chamber, I, near the top of the same, which chamber connects by a proper coupling at its lower end with the feed-delivery oil-pipes X to the cylinders or other parts.

J is a three-way valve near the lower end of the chamber I, having the receiving-opening J' and the three delivery-openings $j j' j^2$, graduated in size for regulating the amount of feed from the chamber I to the pipe X.

K is a curved scale secured to the outside of the chamber I, having scores or marking upon it by means of which the pointer-arm k on the stem of the valve J can be set so that either of the openings j , j' , or j^2 can be turned to communicate with the pipe X.

L is a tube, which opens into the tube c^2 above the communication of the same with the steam-pipe C, and is controlled by the valve l . The said tube L divides into branches $l' l''$ below, each of which runs to and passes through the side of a chamber, I, and has attached to its end a nozzle, l' , which depends in said chamber. On the top of each chamber I is made an oil-cup, M, the opening m of which is engaged by the conical pointed valve m' , the threaded stem of which engages the threaded opening of the standard m^2 , rising inside the cup. By means of the said cup the chamber may be fed with oil when desirable and the feed regulated by the valve m' .

Q is a covering used for the oil-reservoir A. The said covering is composed of a layer, q , of sheet metal over one or more layers, $q' q''$, of a suitable non-conducting material—such as felt—and is secured in position on the reservoir

A by screw-rings q^2 , engaging properly-threaded flanges q^3 , and having retaining or holding flanges q^4 for the edges of the layers of the covering. It is obvious that this covering Q may, if desired, be applied to the various pipes and oil-cups of the device, being suitably secured theron in any convenient manner.

By means of the dam G and formation of the tube E the valve F is water-packed, and the oil and any impurities rising from the reservoir and visible feed-tubes cannot attach themselves to the valve or other parts so as to clog the same.

On account of the steam-pipe C rising from the dome c to the condenser the water condensed in said pipe will flow back into the dome, and will carry with it the impurities coming with the steam from the boiler, so that the water in the reservoir will be practically free from said impurities.

In consequence of the pipe L running from a higher point of the tube c^2 than the steam-pipe, the steam passing through said pipe L will be more nearly free from water of condensation and impurities, all such that exist falling back into the condenser.

Should the openings in the three-way valve J clog, the water of condensation from the nozzle l^2 will collect above said valve and will wash all particles of oil and foreign matter from said openings and clear the same.

Having described my invention, I claim as new and desire to secure by Letters Patent—

1. In a lubricator, the combination, with the oil-reservoir, condenser, and oil and steam chamber, constructed substantially as described, of the tube rising from the top of the condenser, the steam-pipe ascending from the dome of the boiler to said tube, the steam-pipe running from a point of said tube above its communication with the steam-pipe from the dome to the oil and steam chamber, and the nozzle on the end of the steam-pipe from condenser, and depending in the oil and steam chamber, substantially as specified.

2. In a lubricator, the combination, with the oil and steam chamber and the mechanism, substantially as described, for feeding the same with steam and oil, of the three-way valve, the stem of said valve being provided with a pointer-arm, and there being a curved scale secured to the outer side of the chamber and marked in such manner that the pointer can be turned thereon to make any one of the discharge-openings of the valve communicate with the discharge-opening of the chamber, substantially as specified. 50

3. In a lubricator, the combination, with the condenser, reservoir, oil and steam chamber, visible feed-tubes, and oil-feed tubes on the interior of the reservoir, of the horizontal tubes E, having the partitions e and partial partitions or dams G, and the check-valves F, substantially as specified. 60

4. In a lubricator, the combination, with the reservoir A, provided with the flanges q^3 , threaded on their edges, of the screw-rings q^2 , and covering Q, composed of the inner layers, q^4 , of non-conducting material, and outer layer, q^5 , of sheet metal, substantially as specified. 70

5. In a lubricator, the combination, with the condenser, oil-reservoir, steam and oil chambers I, visible feed-tubes, and oil-feed tubes on the interior of the reservoir, of the tube c^2 , rising from the top of the condenser, steam-pipe C from the dome of the boiler to the said tube, steam-pipe L from the tube c^2 to the chambers I, nozzle l , three-way valve J, provided with the pointer-arm k and scale K, 80 and tube E, having the partition e and partial partition G, and valve F, all constructed and arranged substantially as and for the purpose specified. 75

In testimony that I claim the foregoing as my own I affix my signature in presence of two witnesses.

ELIJAH McCOY.
